(57) CLAIM

The ornamental design for a combination wipes and toilet paper holder, as shown and described.

DESCRIPTION

FIG. 1 is a front side perspective view of a combination wipes and toilet paper holder, showing our new design; FIG. 2 is a bottom side perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken line showing of combination wipes and toilet paper holder is included for the purpose of illustrating portions of the "article" and forms no part of the claimed design.

1 Claim, 8 Drawing Sheets
